Attest.

United States Patent Office.

CHARLES H. EMBREE, OF WEST DRESDEN, NEW YORK.

Letters Patent No. 73,704, dated January 28, 1868.

GATE.

The Schedule referred to in these Letters Patent and making part of the same.

TO ALL WHOM IT MAY CONCERN:

Be it known that I, CHARLES H. EMBREE, of West Dresden, in the county of Yates, and State of New York, have invented a certain new and useful Improvement in Gates; and I do hereby declare that the following is a full and exact description thereof, reference being had to the accompanying drawings, making part of this specification.

Figure 1 is an elevation of a farm-gate, arranged in my improved manner.

Figure 2, a perspective view of the swivelled suspension-loop, and the end of the rail that rests therein.

Like letters of reference indicate corresponding parts in both figures.

My improvement belongs to that class of gates that slide part way back, and then swing around.

The invention consists in providing the swivelled suspension-loop, holding the gate, with an extended stem drilled with holes, whereby said gate may be elevated or lowered; and in providing it with inclined slots in the sides, for the insertion and removal of the friction-roller at pleasure, without withdrawing the axis from the roller.

As represented in the drawings, A A are two posts, between which rests the gate B. This gate is composed of the usual rails and battens, a a, b b. The rear post is provided with a projection or bearing, c, which sustains the swivelled suspension-loop C, through which the upper rail of the gate runs. This loop consists of two sides, d d, with a friction-roller, f, at the bottom, and an extended stem, g, which forms the axis, extending up through the projection c, and provided with a series of holes, h h, in any of which rests a pin, i. I prefer to insert a washer, k, under the pin i, on top the projection c, to prevent wear and lessen friction. The axis of the friction-roller is inserted in inclined slots, l l, as clearly represented, by which means it is readily removable at any time without withdrawing said axis from the roller.

A great variety of swivelled-roller devices for gates have before been known. The great advantage of this over others is, that the extended stem g allows the gate to be elevated or lowered, when desired, with the greatest facility, and the inclined slots, l allow the roller to be inserted or removed at any time when it is desired to apply or remove the gate, without detaching the stem g from its bearing.

I am not aware that these combined features have ever before been employed with a swivelled suspension-loop, as above set forth. The suspending of the loop, instead of locating it on the bearing c, is not only more advantageous in practice, but I avoid the use of double posts at the end where the gate swings.

What I claim as my invention, and desire to secure by Letters Patent, is—

The arrangement and use of the adjustable extension-stem g and the inclined slots l l with the swivelled suspension-loop C, operating in the manner and for the purpose herein set forth.

In witness whereof, I have hereunto signed my name in the presence of two subscribing witnesses.

CHAS. H. EMBREE.
